Patented Dec. 14, 1965

203,192

ARTICULATED FISHING LURE

William F. Hiatt, Rte. 10, Lexington, N.C.

Filed Oct. 16, 1964, Ser. No. 82,196

Term of patent 14 years

(Cl. D31—4)

Fig. 1.

Fig. 2.

FIGURE 1 is a perspective view showing the top and one side of the articulated fishing lure;

FIGURE 2 is an elevation view of the articulated fishing lure.

The undisclosed bottom portion of the lure is substantially the same as the top portion except for the inclusion of the hook member.

I claim:

The ornamental design for an articulated fishing lure, as shown and described.
